FEEDING DEVICE FOR PERCUSSIVE MOTORS

Application filed January 30, 1930. Serial No. 424,617.

This invention relates to feeding devices, but more particularly to a device of this character adapted for actuating a percussive motor relatively to its support.

One object of the invention is to utilize 5 the force of the reciprocating piston of the motor for advancing the motor relatively to its support.

Another object is to prevent recoil of the 10 motor upon reversal of the piston at the end of one stroke and to enable the motor to be moved along the support by the piston upon the reversal of the piston at the end of its return stroke.

Another object is to provide a rugged and 15 efficient feeding device requiring a minimum of parts and which device is therefore comparatively inexpensive to manufacture.

Other objects will be in part obvious and 20 in part pointed out hereinafter.

In the accompanying drawings illustrating 25 the invention and in which similar reference characters refer to similar parts,

Figure 1 is a longitudinal elevation, partly 30 in section, of the feeding device showing it operatively connected to a reciprocating motor and its support,

Figure 2 is a transverse view taken through 35 Figure 1 on the line 2-2 looking in the direction indicated by the arrows, and

Figure 3 is a similar view taken through 40 Figure 1 on the line 3-3 looking in the direction indicated by the arrows and illustrating more particularly the means whereby the direction of rotation and therefore the direction of movement of the motor 45 on the support may be controlled.

Referring more particularly to the drawings, A designates a motor which, for the 50 purpose of this invention, is illustrated as a rock drill mounted slidably on a support B illustrated as being a rock drill shell. The motor A comprises the usual cylinder C wherein is disposed a reciprocating hammer piston D to deliver blows of impact against a working implement (not shown).

The support or shell B has the usual guideways E to slidably receive ribs F carried by the cylinder C of the motor.

The cylinder C may be provided with the

usual back head G which may be clamped to the cylinder C by means of side rods H disposed on opposite sides of the cylinder in a well known manner. The back head G serves as a housing for a throttle valve J whereby the admission of pressure fluid into the motor may be controlled and the distribution of pressure fluid to the ends of the cylinder may be effected by any suitable and well known distributing valve (not shown).

In accordance with the present invention, means are provided for enabling the motor A to be moving longitudinally of the support B by the jar resulting upon the reversal of the hammer piston D. To this end an internally threaded nut K is disposed within a bore L of a lug O carried by the motor A. At the front end of the nut K is a flange P which is adapted to seat against the lug O, and the rear end of the nut K is externally threaded and extends rearwardly of the lug O to receive a nut Q whereby the nut K may be fixedly clamped in position.

Extending through the nut K is a screw R having threads S preferably of a fast pitch to engage the threads in the nut K. The front end of the screw S may be supported in any suitable manner by the corresponding end of the support B. The rear end of the screw S is in this instance supported by a cross head T which forms a bearing for the screw S and which in turn is supported by standards U in the form of bolts connected to the support B and having sleeves V disposed thereon to act as spacers for holding the cross head T in spaced relation with respect to the rear end of the support B.

The connection between the nut K and the screw S and the pitch of the threads of these elements are such that when the motor A is 90 moved longitudinally of its support, the screw S will be freely rotated by the motor in either a right or left hand direction, depending upon the direction in which it is desired to move the motor.

Means are provided to hold the screw S immovable and unaffected by the jar resulting at the instant of reversal of the piston D and thus prevent recoil of the motor A when the piston reaches either the front or rear end 100

of the cylinder C. To this end a ratchet W is disposed fixedly on the screw S, either by keying it thereto or, as illustrated, by providing the ratchet W with a polygonal bore X to engage a correspondingly shaped portion Y of the screw S.

On the periphery of the ratchet W are teeth Z and a casing b encircles the ratchet W to form a housing therefor and said casing is secured to the cross head T by means of the standards U. The cross head T thus forms a cover for one end of the casing b. On the opposite or rear end of the casing b is a cover in the form of a plate c which may be secured to the casing b by means of screws d and by nuts e which are threaded on the ends of the standards U to clamp the cross head T, the casing b and the cover c securely in position.

Near the opposite ends of the casing b are formed bores f to act as guides for plungers g which are adapted to act as abutments for the teeth Z of the ratchet W. The plungers g and therefore the bores f may be of any suitable cross sectional form. In the outer portions of the bores f are disposed springs h which bear against the plungers g with one end and with their other ends against plugs j threaded into the outer ends of the bores f.

In order to enable the plungers g to be selectively moved into and out of the path of the teeth Z, said plungers are provided with oblong slots k to receive eccentrically disposed portions o of a rod p. The portions o are offset with respect to each other so that when one plunger g is in the engaging position, the other plunger g will be removed from the path of the teeth Z. The rod p may be suitably journaled in the casing b and is provided with a suitable gripping portion q whereby it may be manually rotated.

Preferably the opposite end of the rod p projects beyond the casing b, and said end is threaded to receive a nut r which acts as a seat for one end of a spring s interposed between the nut r and the casing b to resist free rotation of the rod p.

Suitable braking means may be provided to retard the rotary movement of the screw S. The means for this purpose comprises a brake t which is pivoted on a bolt u threaded into the cross head T, having a shoe portion v adapted to bear against a flange w carried by the screw S. The brake t may be provided with a suitable lever x against which pressure may be manually applied to press the shoe v against the flange w.

The operation of the device is as follows: Let it be assumed that the motor A is in operation so that the hammer piston D is reciprocating rapidly within the cylinder C to deliver its blow to any suitable working implement, such as a drill steel. When the motor A is being thus utilized, it is, of course, essential that it be actuated longitudinally of its support B in the direction of the work so

that the full force of the hammer piston may be effectively applied to the working implement to drive it into the work.

In order to constantly assure this position of the motor with respect to its working implement the rod p may be manipulated so that one of the plungers g, in this instance the plunger g adjacent the gripping portion q, will be moved into the path of the teeth Z of the ratchet W. In this position of the rod p the other plunger g will of course be removed from the path of the teeth Z. When the piston D then moves forwardly to deliver its blow against the working implement, a jar will be imparted to the motor A due to the act of reversal of the piston and the motor A will be bodily advanced along the support B for a distance corresponding approximately to the degree of penetration of the working implement into the work. This movement of the motor A will cause the screw S to describe a partial revolution, and the engaging plunger will then be moved out of the path of the teeth Z by the pressure of the teeth against the front end of said plunger.

Upon the return stroke of the piston D a similar jar will be imparted to the motor A. The motor A will, however, be prevented from recoiling on the support B by the teeth Z, one of which will then bear against the side of the engaging plunger g. From this point on the cycle of operations may be repeated, and upon each forward stroke of the hammer piston D, the motor A will be advanced somewhat along the support.

After the motor A has traveled the required distance on the support B and it is again desired to return said motor to its initial position preparatory to another operation, the hammer piston D may be permitted to continue operating and the rod p is rotated to move the previously engaging plunger g to the releasing position and the other plunger g to the engaging position. In the new positions of the plungers g the screw S will be held immovable and thus prevent recoil of the motor A in a forward direction when the piston D reverses at the end of its forward stroke, and upon reversal of the piston at the end of its rearward stroke, the screw S is free to rotate. The motor A will then be rapidly actuated in a rearward direction by the action of the piston D.

Whenever the motor and therefore the support B are placed in a vertical position so that the motor, due to its own weight, would otherwise tend to move rapidly downward along the support B, pressure may be applied to the lever X and in this way the brake shoe v may be pressed against the flange w to retard the movement of the screw S and in this manner control the speed of the motor along its support.

We claim:

1. In a feeding device, the combination

with a motor and a support whereon said motor is slidably mounted, a reciprocatory hammer piston in the motor imparting jars thereto tending to move the motor longitudinally of the support, of recoil resistance means operatively connected to the motor and the support and comprising a pair of members in threaded engagement with each other and one of which members is adapted to be rotated by the motor upon movement thereof on the support, and stop means for selectively controlling the direction of rotation of the rotatable member to enable the motor to be advanced and retracted with respect to the support by the piston.

2. In a feeding device, the combination with a motor and a support whereon said motor is slidably mounted, a reciprocatory hammer piston in the motor imparting jars thereto for moving the motor longitudinally of the support, a recoil resistance means for the motor operatively connected to the motor and the support and comprising a pair of members in threaded engagement with each other and one of which members is adapted to be rotated in either direction by the motor upon movement thereof on the support, a toothed ratchet carried by the rotatable member, and means forming an abutment for the teeth on the ratchet to hold the rotatable member immovable and thus prevent recoil of the motor

3. In a feeding device, the combination with a motor and a support whereon said motor is slidably mounted, a reciprocatory hammer piston in the motor imparting jars thereto for moving the motor longitudinally of the support, of recoil resistance means for the motor operatively connected to the motor and the support and comprising a pair of members in threaded engagement with each other and one of which members is adapted to be rotated in either direction by the motor upon movement thereof on the support, a toothed ratchet carried by the rotatable member, a pair of spring pressed plungers to form abutments for the teeth on the ratchet to hold the rotatable member stationary and thus prevent recoil of the motor at the instant of reversal of the piston, and means for selectively moving the plungers into and out of the path of the teeth.

4. In a feeding device, the combination with a motor and a support whereon said motor is slidably mounted, a reciprocatory hammer piston in the motor imparting jars thereto for moving the motor longitudinally of the support, of an internally threaded member carried by the motor and fixedly secured thereto, a screw in threaded engagement with the member and being supported by the support, said screw being rotated by the motor upon movement of the motor along the support, a toothed ratchet affixed to the screw, a casing for the ratchet, a pair of spring pressed plungers in the casing to

form abutments for the teeth on the ratchet to hold the screw stationary and thus prevent recoil of the motor upon reversal of the piston at the end of a stroke in one direction and to release the ratchet for permitting the motor to be actuated along the shell by the piston upon reversal of the piston at the end of its opposite stroke, and means for selectively moving the plungers into and out of the path of the teeth to enable the motor to be advanced and retracted with respect to the support.

5. In a feeding device, the combination with a motor and a support whereon said motor is slidably mounted, a reciprocatory hammer piston in the motor imparting jars thereto for moving the motor longitudinally of the support, of a threaded nut affixed to the motor, a screw in threaded engagement with the nut and being supported at its ends by the support, said screw being rotated by the motor upon movement of the motor relatively to the support, a toothed ratchet affixed to the screw, a casing, a pair of spring pressed plungers in the casing to form abutments for the teeth on the ratchet to hold the screw stationary and thus prevent recoil of the motor upon reversal of the piston at the end of a stroke in one direction and to release the ratchet for permitting the motor to be actuated relatively to the shell by the piston upon reversal of the piston at the end of its opposite stroke, a rod, and eccentrically disposed portions on the rod for simultaneously moving one plunger into and the other plunger out of the path of the teeth, thereby permitting the screw to be rotated in only one direction and the motor to be actuated only in one direction on the support during each complete cycle of operation of the piston.

6. In a feeding device, the combination with a motor and a support whereon said motor is slidably mounted, a reciprocatory hammer piston in the motor imparting jars thereto for moving the motor longitudinally of the support, of a threaded nut affixed to the motor, a screw in threaded engagement with the nut and being supported at its ends by the support, said screw being rotated by the motor upon movement of the motor relatively to the support, a toothed ratchet affixed to the screw, a casing, a pair of spring pressed plungers in the casing to form abutments for the teeth on the ratchet to hold the screw stationary and thus prevent recoil of the motor upon reversal of the piston at the end of a stroke in one direction and to release the ratchet for permitting the motor to be actuated relatively to the shell by the piston upon reversal of the piston at the end of its opposite stroke, a rod, and eccentrically disposed portions on the rod and offset with respect to each other to selectively move the plungers into abutting positions for enabling

the motor to be advanced and retracted with respect to the support by the piston.

7. In a feeding device, the combination with a motor and a support whereon said motor is slidably mounted, a reciprocatory hammer piston in the motor imparting jars thereto for moving the motor longitudinally of the support, of recoil resistance means for the motor operatively connected to the motor and the support and comprising a pair of members in threaded engagement with each other and one of which member is adapted to be rotated in either direction by the motor upon movement thereof on the support, a toothed ratchet carried by the rotatable member, a pair of spring pressed plungers to form abutments for the teeth on the ratchet to hold the rotatable member stationary and thus prevent recoil of the motor at the instant of reversal of the piston, means for selectively moving the plungers into and out of the path of the teeth, and brake means adapted to act on the rotatable member to retard rotation thereof.
- 25 8. In a feeding device, the combination with a motor and a support whereon said motor is slidably mounted, a reciprocatory hammer piston in the motor imparting jars thereto for moving the motor longitudinally of the support, of a threaded nut affixed to the motor, a screw in threaded engagement with the nut and being supported at its ends by the support, said screw being rotated by the motor upon movement of the motor relatively to the support, a toothed ratchet affixed to the screw, a casing, a pair of spring pressed plungers in the casing to form abutments for the teeth on the ratchet to hold the screw stationary and thus prevent recoil of the motor upon reversal of the piston at the end of a stroke in one direction and to release the ratchet for permitting the motor to be actuated relatively to the shell by the piston upon reversal of the piston at the end of its opposite stroke, a rod, eccentrically disposed portions on the rod for simultaneously moving one plunger into and the other plunger out of the path of the teeth, thereby permitting the screw to be rotated in only one direction and the motor to be actuated only in one direction on the support during each complete cycle of operation of the piston, and a manually operable brake adapted to act on the screw for selectively retarding rotation thereof.

In testimony whereof we have signed this specification.

WILLIAM A. SMITH, Sr.
